REMINDER CARD RACK

Dale S. Ellis, De Motte, Ind. 46310, and Harriett Rex
Smith, Rte. 7, Box 64, Valparaiso, Ind. 46383

Filed May 19, 1975, Ser. No. 578,491

Term of patent 14 years

Int. Cl. D6—04; D19—02
U.S. Cl. D19—90

FIG. 1

FIG. 2

FIG. 3

FIG. 5

FIG. 1 is an enlarged perspective view of a reminder card rack showing our new design, the indicia which is shown in broken lines is for illustrative purposes only and does not form a part of the claimed design;

FIG. 2 is a top plan view thereof;

FIG. 3 is a bottom plan view thereof;

FIG. 4 is a front elevational view thereof; and

FIG. 5 is a side elevational view thereof, the side opposite of FIG. 5 being substantially identical thereto.

The rear thereof is plain.

We claim:

The ornamental design for a reminder card rack, as shown and described.
